UNITED STATES PATENT OFFICE.

CHARLES E. PRIOR AND ROY J. TAYLOR, OF BALDWINSVILLE, NEW YORK.

INDICATOR.

1,260,576.

Specification of Letters Patent. Patented Mar. 26, 1918.

Application filed December 7, 1916. Serial No. 135,684.

To all whom it may concern:

Be it known that we, CHARLES E. PRIOR and Roy J. TAYLOR, citizens of the United States, residing at Baldwinsville, in the county of Onondaga and State of New York, have invented certain new and useful Improvements in Indicators, of which the following is a specification.

This invention relates to indicators, and 10 more particularly to an indicator for use on street cars and similar vehicles to indicate the various stations or stops.

One of the main objects of the invention is to provide an indicator of the character 15 stated of simple construction and operation provided with a plurality of removable plates upon which the names of the various stations are marked. A further object is to provide an indicator having an endless 20 carrying medium for the plates the direction of travel of which may be quickly and easily reversed. A still further object is to provide simple and efficient means for moving the plate carrying medium intermittently 25 through predetermined distances. Further objects will appear from the detailed description.

In the drawings:

Figure 1 is a front view of the indicator; 30 Fig. 2 is an end view;

Fig. 3 is a vertical transverse sectional view taken closely adjacent one end of the indicator casing;

Fig. 4 is a fragmentary detailed sectional 35 view taken through the chain and the brackets carried thereby;

Fig. 5 is a detail of the ratchet wheel;

Fig. 6 is a detail of the operating mechanism;

Fig. 7 is a fragmentary detail section 40 taken through the ratchet wheel and the rack;

Fig. 8 is a detail of the reversible detent for engaging the ratchet wheel; and

Fig. 9 is a fragmentary view of the drive 45 shaft.

The sheet metal casing 1 is of approximately rectangular shape in transverse cross section and is provided, at its upper edge, 50 with a longitudinally extending hood 2, a rectangular cut-out or opening 3 being provided in each end plate 4 of the casing adjacent this hood. At the lower end of casing 1 a longitudinally extending shaft 5 is 55 rotatably mounted through the end plates 4. One end of this shaft projects through one

of the end plates, as at 5^a. A ratchet wheel 6 is keyed on the projecting end 5^a of shaft 5 and is provided, on its outer face, with a plurality of equally spaced radially extending 60 teeth or ribs 7 of rectangular cross section. A quadrantal rack 8 is loosely mounted on the projecting end 5^a of shaft 5 in front of ratchet wheel 6, being secured against movement axially of the shaft by 65 means of a collar 9 which is secured on the shaft.

The quadrant 8 is provided with a spring 70 pressed detent 10 adapted to engage the teeth of ratchet wheel 6. The head of this 70 detent is beveled upwardly and outwardly as at 10^a. The detent 10 is provided with an integral reduced stem 11 which is 75 slidably mounted through the quadrant 8, an expansion spring 12 being mounted about this stem and confined between the quadrant and the shoulder of the head of detent 10. This spring acts to normally force the 80 detent toward the ratchet wheel 6 so as to engage the teeth thereof. The outer portion 80 of stem 11 of the detent extends through a central bore 13 in an enlarged knob or head 14 which is mounted concentric with the stem. A pin 15 is inserted through stem 11 and projects to each side thereof, the projecting portions of this pin engaging into 85 grooves 16 formed in the head 14 and communicating with the central bore 13. By this means the detent is secured against rotary movement relative to the head, while 90 being free for outward movement. The head 14 is provided with two diametrically opposite radially extending ears 17. These ears are adapted to engage between two spaced lugs 18 formed integral with, and extending outwardly from the outer face of, 95 the quadrant 8. By this means the head 14, and consequently the detent 10, will be normally secured against rotary movement.

A horizontally disposed rack-bar 19 is 100 slidably mounted in a bracket 20 secured to the end of the casing 1. The teeth of this bar are in mesh with the teeth 8^a of the quadrant 8. A coil spring 21 has one end secured to one end of the bar 19 and the 105 other end secured to an angle-bracket 22 secured to the end of the indicator casing. A cable 23 is secured to the other end of rack-bar 19. With the detent 10 adjusted in one position, when the rack-bar 19 is moved 110 longitudinally away from the angle-bracket 22, by exerting tension on the cable 23, the

quadrant 8 will be rotated a predetermined distance about the shaft 5 independently of the ratchet wheel 6, the inclined surface 10^a of the detent passing over the teeth or 5 ribs 7. When the cable 23 is released spring 21 will act to return the rack-bar to its initial position. This will result in rotating the quadrant in the opposite direction a predetermined distance and, during this reverse movement, the detent will engage one 10 of the teeth 7 of the ratchet wheel positively so as to cause rotary movement of the ratchet wheel, and consequently the shaft 5, through a predetermined distance. By 15 grasping the head 14 and pulling it outward so as to release the ears 17 from between the spaced lugs 18, and then turning the head through an arc of 180°, the position of the detent will be reversed so that, 20 when the cable 23 is tensioned so as to move the bar 19 motion will be imparted to the shaft 5, the quadrant moving freely across the face of ratchet wheel 6 during the return movement of the bar under the action 25 of coil spring 21. This provides simple and efficient means whereby the direction of movement or operation of the indicator may be quickly and easily reversed.

The drive shaft 5 is provided, adjacent 30 each end of the casing 4, with a sprocket wheel 24 keyed thereon. A shaft 25 is rotatably mounted in the casing 1, near the upper inner corner thereof in vertical alignment with shaft 5, and is provided adjacent 35 each end with a sprocket wheel 26 secured thereon in vertical alignment with the sprockets 24. Near the upper front corner of the casing a shaft 27 is rotatably mounted and is provided, adjacent each end, with 40 a sprocket 28 in alignment with the sprockets 24 and 26. These three shafts form a triangular frame adapted to receive a driving belt. A sprocket chain 29 is passed about the three sprockets at each end of the 45 casing, and is operative on inwardly extending flanges 13. These flanges extend inward from the end plates of the casing and form a triangular guide-way connecting the sprockets for the chain, thus serving to support the chain in predetermined position 50 during its operation. The chain 29 is of the usual link construction, being provided with the spaced blocks 31 which are pivotally connected by the links 32. To the outer face of 55 each block 31 is secured an outwardly extending U-bracket 33. The brackets carried by one of the chains 30 are in alignment longitudinally of the casing 1 with the brackets carried by the other chain. The aligned 60 brackets are adapted to slidably receive rectangular plates 34 of sheet metal, or any other suitable material. Each of these plates has printed, on its outer face, the name of some station at which the car on which the 65 indicator is used stops.

An idler shaft 35 is rotatably mounted in the casing adjacent the lower inner corner of the opening provided by the cut-outs 3 in the end plates. The chains 29 are passed about this shaft. When the chains are 70 moved in the direction indicated by the arrow in Fig. 3 of the drawings, the plates 34 will be moved toward the opening at the top of the casing so as to have their outer faces displayed, the plates being exposed in 75 turn. Referring more particularly to Fig. 3 of the drawings, the foremost plate 34^a of the horizontal run of the belt formed by the chains 30 and the plates, is in operative position so as to display the marking on its 80 outer face, this marking being such as to designate some station at which the car stops as "5th Avenue," as shown in Fig. 1 of the drawings. When the drive shaft 5 is again operated this plate 34^a will be moved forward and downward about the idler shaft 35 so as to occupy the position of plate 34^b, the succeeding plate 34^c being then moved into operative position so as to be visible to the passengers in the car. To render the 85 designation of the various plates easily visible, suitable illuminating means, such as the light 36 is mounted in the hood 2. The hood acts to reflect the light downward onto the outer face of the plate thus rendering the 90 same easily visible. When the end of a route has been reached, the detent 10 may be reversed in the manner previously described thus reversing the operation of the drive shaft 5 and the travel of the belt carrying the plates 34. During this operation the plates will first be moved upward so as to be exposed in succession the order in which the plates are rendered visible being 95 reversed. This will be clear from Fig. 3 of the drawings from which it will be evident that, if the direction of travel of the belts be reversed, the plate 34^b will be moved into the position occupied by plate 34^a, thus acting to cover up plate 34^a, the plate 34^b being 100 moved rearward of the casing one space. It will be understood, of course, that the distance through which the shaft 5 is rotated with each operation of the rack-bar 19 is such as to move the belts through a distance 105 corresponding to the space between two of the plates 34. Due to the reversibility of operation of the indicator it is not necessary that the number of plates 34 correspond to the number of stations on the route of the 110 particular car in which the indicator is mounted. This renders it possible to use this indicator on comparatively short routes as well as very long routes.

For the purpose of operating the rack-bar 125 19, the cable 23 may be operated manually, or by any other suitable mechanism. For this purpose an electro-magnetic device, such as that shown in Fig. 6 of the drawings may be employed. A lever 37 is piv- 130

totally mounted near its lower end, as at 38. The upper end of this lever may be secured to the cable 23 as at 23^a. The lever 37 is provided, at its lower end, with an armature 39 which is positioned adjacent the pole of an electro-magnet 40 the ends of the coil of which are connected to the opposite sides of a suitable source of electrical energy, such as the battery 41. A suitable switch 42 may be interposed in the circuit of magnet 40. By operating this switch so as to close the circuit the magnet will be energized and will attract the armature 39. This results in swinging the upper end of lever 37 outward away from the drive shaft 5 so as to cause longitudinal movement of rack-bar 19 thus operating the quadrant 8 and shaft 5 in the manner previously described. The rack-bar 19 will, in practice, be actuated, in any suitable manner, after each stop or station which the car passes so as to indicate the succeeding station at which the car will stop. This provides simple and efficient means whereby the passengers of a car or similar vehicle may be quickly and easily notified of the station at which the car will stop, thus eliminating all danger of confusion and avoiding the inconvenience of a passenger being taken past a station at which it is desired to stop.

There may be slight changes made in the construction and arrangement of the different parts of our invention without departing from the field and scope of the same, and we intend to include all such variations, as fall within the scope of the appended claims, in this application in which a preferred form only of our invention is disclosed.

What we claim is:

- 40 1. In an indicator, a casing having a display opening, a plurality of parallel spaced shafts rotatably mounted in the casing, sprocket wheels secured on said shafts in spaced relation, an endless belt mounted about said sprocket wheels for operation across the display opening and adapted to carry indicating plates, a wheel secured on one of said shafts and provided on its outer face with radial ribs, a quadrant loosely mounted on the shaft adjacent said wheel, a spring pressed detent carried by the quadrant and projecting inwardly therefrom so as to engage the ribs of said wheel, said detent having its head beveled, means for reversing the detent relative to said ribs and for securing it in adjustment, and means for oscillating said quadrant about the shaft.
- 5 2. In an indicator, a casing having a display opening, a plurality of parallel spaced

shafts rotatably mounted in the casing, 60 sprocket wheels secured on said shafts in spaced relation, an endless belt mounted about said sprocket wheels for operation across the display opening and adapted to carry indicating plates, a wheel secured on 65 one of said shafts and provided on its outer face with radial ribs, a quadrant loosely mounted on the shaft adjacent said wheel, a spring pressed detent carried by the quadrant and adapted to engage the teeth 70 of said wheel, the head of said detent being beveled and the detent being provided with a stem slidably projecting through the quadrant, an adjusting head mounted on the outer face of the quadrant 75 and connected to the stem of the detent so as to prevent independent rotary movement thereof while permitting independent longitudinal movement of the detent, means for securing said head in rotary adjustment, and 80 means for oscillating said quadrant about the shaft.

3. In an indicator, a casing having a display opening, a plurality of parallel spaced shafts rotatably mounted in the casing, 85 sprocket wheels secured on said shafts in spaced relation, an endless belt mounted about said sprocket wheels for operation across the display opening and adapted to carry indicating plates, a wheel secured on 90 one of said shafts and provided on its outer face with radial ribs, a quadrant loosely mounted on the shaft adjacent said wheel, a spring pressed detent carried by the body 95 and adapted to engage the teeth of said wheel, the head of said detent being beveled and the detent being provided with a stem slidably projecting through the quadrant, an adjusting head mounted on the outer face of the quadrant and connected to the stem 100 of the detent so as to prevent independent rotary movement thereof while permitting independent longitudinal movement of the detent, said adjusting head being provided with radially projecting diametrically opposite ears and the said quadrant being provided on its outer face with spaced lugs 105 adapted to coöperate with the ears for securing the adjusting head in rotary adjustment, and means for oscillating said quadrant. 110

In testimony whereof we affix our signatures in presence of two witnesses.

CHARLES E. PRIOR.
ROY J. TAYLOR.
